Attorney

UNITED STATES PATENT OFFICE

PAUL AUGUST RENNACK, OF GENESEE DEPOT, WISCONSIN

LEG-HOLDING CASTING

Application filed October 11, 1928. Serial No. 311,877.

This invention relates to a stool structure and pertains particularly to an improved means of securing supporting legs to a top member.

5 The primary object of this invention is to provide a cast article designed to be secured to the under side a stool seat and to receive the ends of legs for the support of the seat in such a manner that ready replacement of 10 any one of the legs may be quickly made without employing nails, screws or other securing devices.

15 The invention broadly contemplates the provision of a casting consisting of a number of connected arms at the free end of each of which a leg receiving socket is formed, the arms being designed to be secured to the under face of a seat body to dispose the sockets in the proper positions 20 for the reception of leg members.

25 The invention will be best understood from a consideration of the following detailed description taken in connection with the accompanying drawing forming a part of the present invention with the understanding, however, that the invention is not confined to any strict conformity with the showing of the drawing but may be changed or modified so long as such changes or modifications 30 mark no material departure from the salient features of the invention as expressed in the appended claims.

In the drawing:—

35 Figure 1 is a side elevational view of a stool equipped with the casting device embodying the present invention;

Figure 2 is a sectional view taken substantially upon the line 2—2 of Figure 1;

40 Figure 3 is a plan view of the casting per se.

45 Referring to the drawing in detail, wherein like numerals of reference indicate corresponding parts throughout the several views, the numeral 1 indicates the body part of the casting from which extends a plurality of arms 2, three being shown in the present instance, at the outer end of each of which arms is formed a receptacle or socket 3.

50 The arms 2 are arranged for attachment to a stool seat such as that indicated by the

numeral 4, with their upper surfaces in the same plane so that firm contact will be made therewith. The central portion of the body after the casting operation is bored as indicated at 5 to receive the bolt 6 which is extended through the seat body 4 and which receives upon its lower end the nut 7 which bears against the under side of the casting. 55

While the present article may be made for use in connection with four legged seats or chairs it is shown as designed for the construction of three legged stools. In order to arrange the legs 8 of the stool at the proper inclination with respect to the seat 4 the socket sleeves 3 are suitably angularly 60 directed from the ends of the arms so that when the casting is secured to the under side of the seat body in the manner described and the legs 8 inserted into the sockets they will be properly angled to support the stool 65 70 in the correct manner.

In order to firmly hold the stool legs in their respective sockets the inner wall of each socket is provided with a series of inwardly projecting wedges 9 each of which 75 is of gradually decreasing height from the top to the lower end thereof where it merges into the wall of the socket as indicated at 10. In this manner when a stool leg is driven into the socket the wedges 9 will 80 gradually cut into the face of the leg and bind the same in the socket holding it against 85 turning or longitudinal movement.

From the foregoing description it will be readily seen that the article herein described 90 when employed in the construction of stools, chairs or other leg supported structures will enable the constructor to more quickly produce a finished article, will give a stronger finished article than is obtained by securing 95 the legs directly in the seat body and will enable the owner of the article to easily replace any leg which might become broken so that the active life of the article will be greatly lengthened.

Having thus described my invention what I claim is:—

1. A casting for use in connection with leg supported articles comprising a body portion designed to be secured to the under side 100

of the article, including a plurality of radially arranged arms, a sleeve formed at the outer end of each arm providing a socket for the reception of a supporting leg, said sleeves having a plurality of wedges formed upon and extending substantially the length of the inner walls thereof for cutting into and holding a leg forced thereinto, said sleeves being arranged in convergent relation and having the arms extending from and flush with the upper or convergent ends thereof.

5 2. A casting for use in connection with leg supported articles comprising a spider body portion having a plurality of radially arranged arms, a plurality of converging sleeve members secured to said arms at the outer ends thereof and integrally formed therewith, and a plurality of tapering wedge shaped leg securing members carried by said sleeves.

10 In testimony whereof I hereunto affix my signature.

PAUL A. RENNACK.
